CLAIM

We claim the ornamental design for a pantiliner, as shown and described.

DESCRIPTION

FIG. 1 illustrates a top plan view of a pantiliner, showing our new design, the bottom plan view being plain and unornamented;

FIG. 2 illustrates a side elevational view thereof, the opposite side elevational view being identical thereto; and, FIG. 3 illustrates a cross-sectional view thereof, and taken along line 3—3 of FIG. 1.

The broken line in FIG. 1, showing a representative shape for a pantiliner, is for illustrative purposes only, and forms no part of the claimed design.
